UNITED STATES PATENT OFFICE

98,460

DESIGN FOR A VIBRATOR BODY

George B. Pickop, New Haven, Conn.

Application December 20, 1934, Serial No. 54,511

Term of patent 14 years

To all whom it may concern:

Be it known that I, George B. Pickop, a citizen of the United States, residing in New Haven, in the county of New Haven and State of Connecticut, have invented a new, original, and ornamental Design for a Vibrator Body, of which the following is a specification when taken in connection with the accompanying drawing.

Fig. 1 is a side elevational view of a vibrator body embodying my design;

Fig. 2 is a side elevational view taken at right angles to Fig. 1;

Fig. 3 is a side elevational view looking from the side opposite that shown in Fig. 2; and

Figs. 4 and 5 are end views of the vibrator body.

I claim:

The ornamental design for a vibrator body substantially as shown.

GEORGE B. PICKOP.
